(57) **CLAIM**

The new original design for “video camera bag,” as shown and described.

DESCRIPTION

FIG. 1 is a front view of a video camera bag showing my new design;

FIG. 2 is a rear view of the bag depicted in FIG. 1;

FIG. 3 is a top plan view thereof;

FIG. 4 is a bottom plan view thereof;

FIG. 5 is a right side elevational view thereof; and,

FIG. 6 is a left side elevational view thereof.

The broken lines shown in FIGS. 1, 2, 3, 5, and 6 are understood to represent stitching.
